METHOD OF GENERATING GAS

Application filed September 22, 1928. Serial No. 307,599.

The primary object of the invention is to provide a method whereby a gas generator may be operated under such conditions as to so control the formation of clinkers, as to prevent the formation of the large clinkers which tend to form in the ash bed, and lower portion of the fire bed in usual methods of operation. Particularly in the production of water gas, clinkers of such large size have been formed that it has been necessary to shut down the generator periodically and take out the clinkers manually with bars and sledge hammers.

Our prior application Serial Number 120, 15 291, filed July 3, 1926, now Patent No. 1,709,335, dated April 16, 1929, entitled "Method of generating gas", contains subject matter in common with the present application, certain generic claims of a scope commensurate with those presented herein having been contained originally in said prior application, together with other claims relating particularly to the manufacture of water gas, and said generic claims having 20 been withdrawn in compliance with the official requirement that they be presented in a separate application from the said claims relating particularly to the manufacture of water gas. The present application therefore 25 is intended to cover the subject matter withdrawn from the claims of the aforesaid prior application for the reasons above mentioned, as well as certain features of the invention as utilized for the purpose of gas enrichment.

30 We have illustrated in the accompanying drawings a gas generator adapted to be operated in accordance with the invention, but it should be understood that this particular gas generator is merely typical of an apparatus suitable for carrying out the invention, and that the principles of the invention are not confined thereto. In the drawings—

Fig. 1 is a central vertical sectional view 35 showing the general construction of a gas generator adapted to be operated in accordance with the invention.

Figs. 2 and 3 are vertical sectional views, partly diagrammatic, respectively showing 40 the full height of a water gas generator and

gas producer adapted to carry out the process of the present invention.

The invention is first described hereinafter as applied to the manufacture of water gas but it is to be understood that it is in a broad 55 sense applicable to the making of producer gas or a mixed gas, or to the enrichment of industrial gases such as blast furnace gas, lime kiln gas, or gases obtained from any reduction process wherein a large percentage 60 of CO must be left.

Gas generators both for water and producer gas have been operated with relatively thick ash beds, with the result that the ash in the lower parts of the ash bed has been relatively cold, and although such ash beds have been agitated to some extent from underneath, this agitation has not proved effective 65 in breaking up very large clinkers, particularly in water gas generation, when once they 70 have been formed, and the effort has generally been made to minimize the formation of large clinkers by keeping the temperatures within the generator as low as possible while still within the limits necessary for producing a commercial grade of gas, the idea being that if the ash content of the fuel bed was kept below its liquefying temperature, there would not be so many large clinker masses 75 formed. Moreover it has been customary to operate water gas generators, so as to maintain under the firebed a bed of thoroughly burned fuel deep enough to submerge the ash agitating member, thereby rendering it unnecessary to water cool said member. 80

According to the present invention the gas generator is operated under such conditions that the temperature of the hottest zone of the fuel bed for the most part is well above the liquefying point of its ash content, whereby liquid ash tends to run down in little rivulets from the hottest zone of the fuel bed, to a slightly cooler zone directly beneath the same which latter zone, although somewhat below the liquefying point of the ash, nevertheless is sufficiently hot to permit the liquid ash, trickling into said zone, to continue its downward flow without losing its mobility until it reaches the small clinkers and partially burned fuel in the neighbor- 95 100

hood of the agitating member, and agitated by it. The melting point of ash in different grades of coal and coke as usually employed, runs between about 1900° and 2700° F. This 5 zone of the ash bed is then subjected to the direct action of an agitating member which sweeps through the slowly solidifying ash, before it can run together and solidify into large masses that cannot be readily broken up.

- 10 We prefer to operate the gas generator in such manner that a very thin ash and clinker bed is maintained. It is not allowed to become thick as is customary in prior practice. The solidifying zone above mentioned will 15 then be located almost upon the grate of the generator, such zone being made up of partially consumed fuel, small clinkers and ash at red heat, with the result that the generator has no thick cold ash bed as heretofore. 20 The agitating member, located directly over the generator grate, is where it will continually break up clinkers as aforesaid, and also thoroughly agitate the lower portion of the fire bed and assist in the uniform removal of 25 the clinker and ash due to its up-and-out stroking action, thereby maintaining good gas making conditions in the firebed. The thin ash bed and the continuous agitation of the firebed make it possible to carry a greatly 30 reduced depth of fire.

By supplying air in sufficient quantity to maintain an ash liquefying zone in the fuel bed, and ejecting clinker and ash at such rate that the solidifying zone will be shallow and 35 kept at a proper heat, the same agitating member may serve to perform continuously all of the above mentioned functions of preventing the formation of large clinkers by breaking up the clinkers as they form, agitating the fuel bed and assisting in the removal of the clinker and ash. For example, 40 from 30 to 50 cubic feet of air (at atmospheric pressure and room temperature) may be used per pound of total steam, the smaller 45 amount of air being used for fuel of low ash melting point and the larger amounts for fuels of higher ash melting point. Agitation in this invention is not "through the medium of the ash" as heretofore, but mostly through 50 the medium of the partially consumed, but still burning, fuel.

The amount of steam fed into the bottom of the generator may also be regulated to control temperature conditions within the 55 generator, the steam acting as a cooling medium, whereas the air fed in acts as a heating medium.

In the production of water gas, furthermore, the up and down runs may be proportioned to maintain ash liquefying and solidifying temperature conditions as above described, so that the clinkers will be properly broken up by the agitating member. The 60 production of water gas usually involves a cycle of operations over a period of three to

eight minutes, the first operation being the passing of a blast of air upwardly through the ash and fuel beds, another operation being an upward run of steam, and a third operation being a downward run of steam, the above operations usually taking up about the same amount of time, the up and down steam being about the same in quantity, according to prior practice.

In accordance with the present invention 75 the upward blast of air will be sufficient in quantity to raise the hottest zone in the fuel bed to such a temperature as may be required to liquefy the major portion of the ash content of the fuel bed. This temperature, with some 80 grades of coke, may be, for example, from about 2700° to 3000° F. The quantity of the up-run steam may be (but is not necessarily) substantially lessened to assist in preventing the lower zone in the firebed from cooling off 85 sufficiently to unduly check the flow of the molten clinker streams before coming within the radius of action of the agitating member. Good results have been obtained with but twenty (20) percent of up-steam runs. This 90 makes a sufficiently increased proportion of down-steam runs, so that it will carry down from the upper zones sufficient sensible heat to assist materially in maintaining at a red heat the major portion of the clinker and ash 95 upon the grate. Because of the high temperature maintained in the bottom of the fire, the steam up-runs may be entirely omitted if blue 100 water gas is desired, or if the gas connections are arranged to pass part or all of the down-run water gas through the carburetor. This does not preclude removing gas from the ash pit by up purges. This unusually large percentage of down-run steam greatly increases the efficiency of water gas generation.

The usual practice in the operation of present day water gas generators involves not more than a 50% ratio of down-run steam to the total steam supplied.

It has been found with certain fuels that 110 gases made in a deep fire bed of the above description, are exceptionally rich in quality, the air blast gases being too high in carbon monoxide for the most efficient operation. A substantially thinner firebed has resulted in 115 substantially reducing the richness of the blast gases, which pass through the firebed at high velocity, without materially reducing the richness of the up and down-run water gases, which pass through the firebed comparatively slowly. The exceedingly high temperature described above and the uniform condition of the firebed, due to continuous agitation, render it unnecessary with some 120 fuels to carry the usual depth of firebed, which is eight (8) to ten (10) feet, in order to obtain a satisfactory quality of gas; a satisfactory quality of gas has been obtained with one half the usual depth of firebed. This reduces the pressure drop through the firebed 125 130

and also reduces the combustible content of the blast gases leaving the fuel bed, thus increasing the efficiency of the operation by developing more heat in the firebed, and carrying away less energy in the blast gases. For example, the blast gases may contain about 14% CO and 14% CO₂.

The invention as illustrated may be carried out in a gas generator similar to the one more fully described in our copending application, Serial Number 737,238, filed September 12, 1924, now Patent No. 1,709,334 dated April 16, 1929, entitled "Gas generator," and accordingly the structural features of the generator will be described only in a general way herein. The gas generator is shown as provided with side walls 1 enclosing the fuel and ash beds and a stationary grate 2 through which air and steam will be passed, as previously described in connection with the production of water gas. As shown, a distributing chamber 3 underlies the grate 2 and is surrounded by an annular ash chamber 4 into which a portion of the ash will be deposited as hereinafter described. A certain amount of ash will also pass down through the grate 2 into the chamber 3.

The agitating member 5 is shown in the form of a water cooled beam extending substantially diametrically over the grate and secured to a drive ring 6 which surrounds the grate and is rotatably mounted upon the bearing ring 7. Suitable water cooling connections 8 may be led through chamber 3 to the agitating member.

In the operation of the generator a zone 9 of the fuel bed which extends down approximately to the line 10 indicated on the drawings, will be maintained at a heat sufficient to liquefy at least most of its ash content, with the result that small streams of the liquid ash run down into the bed or zone 11 beneath the line 10 indicated upon the drawings, which is maintained at a temperature somewhat below the liquefying temperature of the ash (2,000° F. more or less, depending upon the melting point of the ash) but yet at a red heat sufficient to prevent the ash from cooling and taking a set too quickly. The agitating member 5 rotates within the above mentioned zone 11 and therefore directly engages and breaks up the solidifying ash before it can form into large clinkers. The beam should be made of substantial thickness and as shown its forward surfaces preferably are inclined, whereby it exerts a substantial upstroking effect which extends at least into the lower portion of the zone 9 and assists in maintaining good gas making conditions therein.

The beam is also outstroking in its action and tends to crowd the ash outwardly beyond the periphery of grate 2, from whence the ash may pass downwardly through an annular ash discharge opening 12 to a trough

13 provided in connection with the drive ring 5. The rate of ash removal may be controlled by removing ash in any suitable manner in measured quantities from the trough 13, thereby permitting further ash to pass out 70 from the ash bed through the discharge opening 12.

As previously stated, the ash preferably is ejected from the generator at such rate that the zone 11, in which the agitating member operates, is maintained at a shallow depth, whereby the contents of the generator are at a red heat, substantially down to the grate 2.

As shown, the portion of the generator walls surrounding the agitating member 5, are water-cooled by means of the passages 14 in an annular wear member 15. This water-cooling tends to cool down the portion of the generator walls just above the ring 15 85 to such an extent that under ordinary conditions slag deposits would build up which could only be removed manually after shutting down the generator. We have found, however, that if a zone in the fuel bed be 90 maintained well above the ash liquefying temperature, as above described, the ash will quickly flow downwardly past said cooled portion of the generator wall into the radius of action of the agitating member without 95 forming objectionable deposits as aforesaid.

A generator, operated in the above manner, therefore, may be run continuously, the ash being mechanically removed at the proper rate and the fuel and ash beds mechanically 100 agitated from underneath by the beam 5, to assist in maintaining good gas making conditions.

It has long been recognized that the so-called slagging producer is the most efficient 105 type; due to the extremely high temperatures necessary for liquefying the entire ash content of the fuel, but hitherto this type of producer has not proven commercial because of the cost and extreme difficulty of obtaining 110 the required degree of fluidity with most fuels. A modified slagging type is now made possible by the combination of mechanical agitation and proportioning of the blast, and up and down runs above described. This 115 improved method has all of the advantages of the slagging producer and none of its disadvantages, and therefore forms an important part of this invention.

In Fig. 2 we have shown in a general way, 120 a water gas generator having the parts more fully described above in connection with Fig. 1, and also having in its dome at the top, a steam inlet pipe 16 and a similar steam inlet pipe 17 in chamber 3 above described. A 125 gas and blast outlet conduit 18 is also indicated at the top, and air and gas inlet and outlet conduits 18a at the bottom, communicating with chamber 3. Fig. 2 also shows 130 the ash liquefying zone 9 and ash solidifying

zone 10 in proper relation to the full height of the firebed, the upper zone of which firebed is illustrated at 19, and Fig. 2 also indicates diagrammatically at 20, molten ash 5 running down from the ash liquefying zone 9 into the range of action of the agitating member 5.

Fig. 3 shows an apparatus similar to that of Fig. 2 used for making producer gas, the 10 various numerals denoting the same parts as in Fig. 2 with the exception that the upper firebed zone 19a of Fig. 3, will be somewhat shallower than the corresponding firebed zone 19 of Fig. 2.

15 In applying the invention to the enrichment of industrial gases as above mentioned, the steps of operation will be similar to those described above in connection with the manufacture of water gas, except that the up and 20 down runs of steam are not employed as above described (although a certain amount of steam may be used if desired), and instead up and down runs of the industrial gas containing CO and CO₂ are admitted through 25 the inlet openings 16 and 17 above described, with the result that the CO₂ content of the industrial gas is broken up and CO formed. In other words in using the invention for enrichment purposes an up-blast of air may 30 be first passed through the firebed to heat the same up after which an up purge of steam may be passed through, although this is not essential; an up run of industrial gas may then be passed through, followed by a 35 down run of industrial gas, although the latter two steps may be reversed, if desired, or the up-run of gas omitted, particularly if a fairly large steam purge is used.

The gas obtained will be of the producer 40 gas type but usually of higher B. t. u. value; for example, blast furnace gas may be raised from a value of 94 B. t. u. per cubic foot up to 160 B. t. u. or more.

A mixed gas may also be used, containing 45 water vapor as well as CO, or liquid hydrocarbons may be added along with the runs to further improve the B. t. u. value of the gas, for example, through the inlet openings 16 and/or 17 above described in connection 50 with Figs. 2 and 3.

Temperature conditions in the firebed will be controlled by proportioning the amount of air supplied, and the up and down runs to maintain an intermediate ash liquefying zone 55 and lower ash solidifying zone as above described in connection with the manufacture of water gas, whereby the agitation of the firebed breaks up any large clinkers and renders the firebed continuous and mechanically conditioned in its operation for the purpose of gas enrichment.

We claim:

1. The method of making combustible gas 60 of the producer gas type in a firebed containing a zone at an intermediate level and a

second color zone containing ash underneath said first mentioned zone, which includes air-blasting the fuel bed to maintain the first mentioned zone at a temperature sufficient to liquefy a substantial portion of its ash content, passing the liquefied ash content downwardly into said second mentioned zone to solidify it, and breaking up the clinkers in said second mentioned zone while hot and before large masses can form. 70

2. The method of making combustible gas of the producer gas type in a firebed containing a zone at an intermediate level and a second zone containing ash underneath said first mentioned zone, which includes air-blast- 75 ing the firebed to maintain the first mentioned zone at a temperature sufficient to liquefy a substantial portion of its ash content, passing the liquefied ash content downwardly into said second mentioned zone, maintaining the second mentioned zone at a red heat some- 80 what below the ash solidifying temperature, whereby the ash passing downwardly from the first mentioned zone solidifies in the sec- 85 ond mentioned zone, and passing an agitat- 90 ing member through said second mentioned zone to break up clinkers while hot and be- 95 fore large masses can form. 100

3. The method of making combustible gas of the producer gas type in a firebed, which 95 includes air-blasting the firebed and main- 100 taining a zone therein at an intermediate level at a sufficiently high temperature to liquefy a substantial portion of its ash content, passing the liquefied ash content downwardly to a 105 solidifying zone beneath said first mentioned zone and agitating said solidifying zone to 110 break up the clinkers while hot and before 115 large masses are formed. 120

4. The method of making combustible gas 105 of the producer gas type in a firebed, which includes maintaining a zone at an intermediate level in the firebed at a temperature suf- 110 ficient to liquefy a substantial portion of its ash content, passing the liquefied ash content 115 downwardly from said zone to solidify the same, removing ash from the bottom of the firebed at a rate sufficient to leave at the bottom of the firebed only a small amount of ash at a temperature somewhat below the ash so- 120 lidifying point, and passing an upstroking agitating member through the bottom of the firebed to engage and break up the solidified clinkers which tend to form and agitate the firebed from underneath and assist in the re- 125 moval of the ash.

5. The method of making combustible gas in a firebed, which includes separately air- 125 blasting the firebed and passing gases con- 130 taining CO and CO₂ therethrough, to main- 135 tain a zone in the firebed at an intermediate level at a sufficiently high temperature to liquefy a substantial portion of its ash content, passing the liquefied ash downwardly to a solidifying zone beneath said first-men-

tioned zone, and breaking up the clinkers in said second-mentioned zone while hot and before large masses can form.

6. The method of making combustible gas in a firebed, which includes separately air-blasting the firebed and passing gases containing CO and CO₂ therethrough in up and down runs to maintain a zone in the firebed at an intermediate level at a sufficiently high 10 temperature to liquefy a substantial portion of its ash content, passing the liquefied ash downwardly to a solidifying zone beneath said first-mentioned zone, and breaking up the clinkers in said second-mentioned zone 15 while hot and before large masses can form.

7. The method of making combustible gas in a firebed, which includes separately air-blasting the firebed and passing gases containing CO and CO₂ therethrough in up and 20 down runs to maintain a zone in the firebed at an intermediate level at a sufficiently high temperature to liquefy a substantial portion of its ash content, passing the liquefied ash downwardly to a solidifying zone beneath said 25 first-mentioned zone, breaking up the clinkers in said second-mentioned zone while hot and before large masses can form, and injecting a liquid hydrocarbon along with one or more of said runs to further enrich the 30 gas made.

8. The method of making combustible gas in a firebed, which includes separately air-blasting the firebed, purging the firebed by passing steam therethrough and passing gases 35 containing CO and CO₂ therethrough, to maintain a zone in the firebed at an intermediate level at a sufficiently high temperature to liquefy a substantial portion of its ash content, passing the liquefied ash down- 40 wardly to a solidifying zone beneath said first-mentioned zone and breaking up the clinkers in said second mentioned zone while hot and before large masses can form.

Executed at New York, in the county of 45 New York and State of New York, this 16th day of August, 1928.

CHARLES W. ANDREWS.
WILLIAM B. CHAPMAN.
